(21) **Appl. No.:** **29/537,420**

Primary Examiner — John Windmuller

(22) **Filed:** **Aug. 26, 2015**

(57) **CLAIM**
The ornamental design for a radio frequency tag, as shown and described.

Related U.S. Application Data

(62) Division of application No. 29/432,038, filed on Sep. 13, 2012, now Pat. No. Des. 740,261.

Foreign Application Priority Data

Mar. 13, 2012 (CN) 2012 3 0056819

DESCRIPTION

(51) **LOC (10) Cl.** **14-03**

FIG. 1 is a front elevational view of a radio frequency tag showing my new design; and,

(52) **U.S. Cl.**

FIG. 2 is a perspective view thereof.

USPC **D14/230**

The solid black areas constitute the entirety of the claimed design. All elements of the claimed design are flat and coplanar.
